UNITED STATES PATENT OFFICE.

JOSEPH S. MEAD, OF MILWAUKEE, WISCONSIN.

ANKLET OR SPAT.

No. 905,901.

Specification of Letters Patent.

Patented Dec. 8, 1908.

Application filed April 27, 1908. Serial No. 429,364.

To all whom it may concern:

Be it known that I, JOSEPH S. MEAD, a citizen of the United States, residing at the city of Milwaukee, county of Milwaukee and 5 State of Wisconsin, have invented new and useful Improvements in Anklets or Spats, of which the following is a specification.

My invention relates to improvements in anklets or so called spats and it pertains to 10 that class which are first knit in separate parts shown and hereinafter described when said parts are thereafter folded and stitched together in the complete form for use.

The construction of my anklets and the 15 method of forming the same is explained by reference to the accompanying drawings in which,—

• Figure 1 is a plan view of the parts as they are manufactured by the knitting machine 20 preparatory to being folded together, and Fig. 2 represents a side view of the anklet in its completed form.

Like parts are referred to by the same reference figures throughout the several views.

25 The fabric comprising the anklet is first knit in two separate pieces A and B. The outline of the part A is defined and included within the vertical line from 1 to 2, the horizontal zig-zag line from 2 to 3, the diagonal line from 3 to 4 inclining inwardly and down-

wardly from the top toward the center of the fabric, the downwardly and outwardly inclined diagonal line from 4 to 5 and the horizontal base line from 5 to 1. The outline of 30 the part B is defined and included within the horizontal zig-zag lines from 6 to 7, the downwardly and inwardly curved line from 7 to 8, the upwardly curved line from 8 to 9, the horizontal zig-zag line from 9 to 10, the

40 vertical line from 10 to 11, the horizontal zig-zag line from 11 to 12, the inwardly and upwardly inclined line from 12 to 13 and the outwardly and upwardly inclined line from 13 back to 6. When the two fabrics A and B

45 have been thus formed, the two opposing edges comprising the lines 3, 4, and 5, and 12, 13 and 6 are stitched together thereby forming the angular front seam 14 shown in Fig. 2. When this is done the fabric 13 is

50 folded back upon itself between the points 8 and 15 of Fig. 1 when the opposing edges between 7 and 8, and 8 and 9 are stitched to-

gether forming the rear fold 17 of the anklet as shown in Fig. 2. When the anklet has been thus folded and stitched together a series of buttons 18, 18 are secured in the ordinary way to the edge 19 of the fabric and a series of button holes or sockets 20 are secured to the opposite marginal edge 21 whereby when said parts are folded and 55 stitched together said buttons are adapted to engage in said button holes or sockets in the ordinary manner. When the anklet has been thus formed a strap 22 is connected to the opposing sides of its lower edge by 60 stitches or otherwise which strap is adapted to engage beneath the foot of the wearer and thereby hold the anklet in place over the top of the shoe. As a means of giving the anklet or spat the required elasticity and a neat ornamental appearance, the respective fabrics are preferably made up of a plurality of vertical seams 23 and 24, the stitches of the respective seams being formed at an angle to 65 each other. The stitches upon the respective sides of the several vertical lines 25 converging downwardly towards the vertical lines 26 thus giving the fabric a neat ornamental appearance while the fabric produced by such stitch is elastic and adapted to 70 stretch and conform to the shape of the ankle over which it is worn.

Having thus described my invention what I claim as new and desire to secure by Letters Patent is,—

As an article of manufacture an anklet formed of two separate knit members respectively comprising a plurality of vertical seams, the stitches of the respective seams being formed at an angle to each other and 85 alternately converging downwardly and upwardly, whereby the fabric is not only given a neat and ornamental appearance but such fabric is more elastic and adapted to stretch and conform to the shape of the ankle of the 90 wearer, one of said members comprising, when folded and stitched together, one-half of the front, one side, all of the rear portion and one-half of the other side portion of the anklet, the other member being adapted 95 when secured in place to form one-half of the front and one-half of the side of the anklet, means for permanently connecting the opposing angular edge of said members together 100

to form the front of the anklet, means for permanently connecting the opposing edges of the folded member together to form the rear of the anklet and means for temporarily connecting the opposing edges of said member at one side of the anklet all substantially as and for the purpose specified.

In testimony whereof I affix my signature in the presence of two witnesses.

JOSEPH S. MEAD.
